US00D814691S

(12) **United States Design Patent** (10) **Patent No.:** **US D814,691 S**
Clark (45) **Date of Patent:** **** Apr. 3, 2018**

(54) **LIGHTING FIXTURE**

(71) Applicant: **3form, LLC**, Salt Lake City, UT (US)

(72) Inventor: **Bruce Clark**, Redmond, WA (US)

(73) Assignee: **3Form, LLC**, Salt Lake City, UT (US)

(**) Term: **15 Years**

(21) Appl. No.: **29/530,073**

(22) Filed: **Jun. 12, 2015**

Related U.S. Application Data

(63) Continuation of application No. 14/646,232, filed as application No. PCT/US2013/070236 on Nov. 15, 2013, now Pat. No. 9,644,820, application No. 29/530,073, filed on Jan. 15, 2018, which is a continuation-in-part of application No. 14/912,396, filed as application No. PCT/US2014/065816 on Nov. 14, 2014, which is a continuation of application No. 61/905,176, filed on Nov. 16, 2013.
